Des. 2479

Letters Patent No. 2479. Dated Oct. 2, 1866.

Design for a Lamp Globe.

The subject referred to in this Letters Patent, and making part of the same.

to all whom it may concern:

Be it known that Thos. Moore, and James S. Haldeman of Bloomington in the County of McLean and State of Illinois have invented a new and Improved Design for a Lamp Globe or Globe, and we do hereby declare that the following is a full, clear and exact description thereof, which will enable others skilled in the art to make and use the same, preference being had to the accompanying drawings forming part of this Specification which is a full perspective view of the same.

The novelty of design consists in the globe being pear shaped, the largest end being the top of the globe, this in differing from any globe in use, being the inverse, or contrary of the usual design for such and in their extreme shortness.

These may be constructed by being blown or moulded of flint lime, or common white glass after the manner in use and well known in glass factories. Their average length should be three and a half inches, have an inch over or under that length being immaterial, their greatest diameter at Fig. 1 being at two thirds their length from the bottom of the globe and neither more or less than two, and therefrom inched greatest diameter should be the rule.

The neck or aperture at the top B, Fig. 1, should not be more than one inch and one fourth, nor less than one inch and one eighth in diameter.

Having thus described our invention we claim as new and desire to secure by Letters Patent for the term of seven years,

A Design for a lamp Globe or Globe substantially as described and shown.

Witness,

John Birch,
David Birn.

Thos. Moore

J. S. Haldeman,
